UNITED STATES PATENT OFFICE.

WILLIAM FONTAINE LITTLE, OF NEPPERHAN, NEW YORK, ASSIGNOR TO THE BALTIMORE ENAMEL & NOVELTY COMPANY, OF BALTIMORE, MARYLAND, A CORPORATION OF MARYLAND.

SHADE AND SOCKET HOLDER.

1,110,066.

Specification of Letters Patent.

Patented Sept. 8, 1914.

Application filed November 13, 1912. Serial No. 731,093.

To all whom it may concern:

Be it known that I, WILLIAM F. LITTLE, citizen of the United States of America, residing at Nepperhan, county of Westchester, State of New York, have invented certain new and useful Improvements in Shade and Socket Holders, of which the following is a specification.

This invention relates to a fitting or fixture for incandescent electric lights, and particularly to a mounting for the hood or reflector shade, preferably combined with means for supporting a lamp socket.

The details of the supporting members are especially adapted and devised for use in connection with a one-piece hood or shade of the kind which has a neck or portion of reduced diameter at the top, in which the socket and a part of the bulb are inclosed. However, the invention may be otherwise applied, the purpose being to provide for convenient access to the socket and the ends of the wires.

Commonly the end of the conduit is threaded and the upper end of the shade is provided with a nut or threaded boss to engage the thread; or the conduit may be provided with a flange spaced back from its edge and the lower portion of the conduit threaded to receive a nut or other threaded member, as a specially formed socket by means of which the shade is forced up against the flange. The end of the conduit ordinarily enters an aperture in the hood and the hood is fastened to and supported by the conduit. The socket is also supported on the end of the conduit or in some similar manner and is located within the neck at its upper end. The device is generally set up and the connections made as follows:

A double length of wire is connected at its two ends with the terminals of the socket and threaded through the aperture in the shade. The length of wire above the hood is then passed up the conduit and connected to the terminals provided for that purpose, in the box where the conduit branches. The shade is then fastened by any suitable means as described above, to the end of the conduit. Under these circumstances, the only way to get at the socket for purposes of repair or replacement, is to disconnect the wires at the box and draw them out of the conduit.

Some types of fixtures are provided, in which the wires may be disconnected from

the sockets from below but even in this case it is very difficult to replace the socket when it has once been removed without disconnecting at the box, or some equivalent operation, as the ends of the wires are necessarily short and brittle.

The object of the present invention is to provide a fixture of this general type, which may be applied to the end of any conduit by merely cutting a suitable thread thereon, and which is so constructed that the hood may be easily displaced and moved up the conduit to uncover the socket without disconnecting the wires. The socket is likewise supported so that it may be conveniently removed and replaced.

With this end in view, a sleeve or boss is provided which is screw threaded internally to engage the lower end of the conduit and provided with a flange or other abutment at its lower end. Above the flange, the sleeve is screw threaded externally and an internally threaded ring or nut is provided to engage the thread on the outside of the sleeve, the shade or hood being provided with an aperture to receive the threaded portion of the sleeve.

To set up the device, the ring or nut is first passed on to the conduit and the shade is passed up the conduit beneath the nut, the conduit extending through the aperture in the shade. The sleeve is then screwed on to the end of the conduit its threaded end extending through the aperture in the shade, and the nut or threaded ring is screwed down over the boss or sleeve pressing the shade against the flange thereon. When it is desired to get at the socket, this may be very conveniently done by unscrewing the nut and sliding the shade up the conduit, when free access may be had to the socket.

In the preferred form of my invention, the socket is supported on a bracket which consists of a ring to inclose the sleeve to which I have referred, and a plurality of arms radiating from the ring. These arms are deflected downward and are provided at their ends with gripper jaws adapted to engage the socket, the latter being preferably of the type which consists of a cup portion having a shoulder near the center of its outer surface, and is externally threaded above the shoulder, and provided with a flanged ring of copper or other metal having a thread

to fit the thread of the cup. The arcuate ends of the arms or grippers of the bracket are held between the shoulder of the cup and the flange of the ring. The upper end 5 of the boss or sleeve may be passed through the ring which forms the support for the bracket before it is screwed on the end of the conduit beneath the shade, or the ring may be passed over the end of the conduit before 10 the sleeve is applied thereto. When the nut is screwed down against the shade to hold it in place the bracket is also clamped and held rigidly in place. To remove the socket it is only necessary after sliding the shade up 15 the conduit to get it out of the way, to unscrew the socket ring, say half a turn, and remove the socket from the bracket; the arms being of thin sheet metal give sufficiently to permit convenient removal of the 20 socket. Any other type of socket adapted to engage the gripper ends of the arms may be used.

In the accompanying drawing, I have illustrated a fixture embodying the various 25 features of my invention in their preferred form.

Figure 1 is a vertical central cross section of the device, Fig. 2 is an elevation. Fig. 3 is a view of the socket support or 30 bracket.

Referring to the drawings by the numerals which are placed thereon to indicate the various parts: The conduit 1 is preferably threaded at its lower end at 2 to receive the 35 flanged sleeve 3 which is internally threaded to fit the conduit or otherwise adapted to be fastened thereto, and externally threaded at 4 to receive the nut or ring 5 which is correspondingly threaded. The 40 reflector shade or hood 6 which in its preferred form is made of metal and enameled to resist the weather, is apertured at 7 to receive the reduced portion of the sleeve 3 above the flange. The aperture 7 is prefer- 45 ably provided with an eyelet or flanged sleeve 8 adapted to be gripped between the nut 5 and the flange or abutment 9 of the sleeve to protect the enamel of the shade and also to form a water-tight joint, the metal 50 of the eyelet being sufficiently soft to be easily compressed when the nut is tightened.

In the preferred form of my invention, the socket 10 is formed of a porcelain cup 11, having a peripheral shoulder at 12, and 55 is threaded above the shoulder at 13. A thin metal ring 14 threaded to engage the thread 13 closes the upper end of the porcelain cup. This is flanged at 15 forming a grip for the ends of the bracket arms as hereinafter 60 described. The socket is supported on the bracket 16 which consists of a ring 17 to engage the threaded portion of the sleeve 3 and having a plurality of depending arms 18. At the lower end of each arm, is a flat 65 arcuate gripping member 19 adapted to en-

gage the cup and to be gripped between the shoulder 12 and the flange 15. The arms 18 are made of thin metal and may be easily flexed to permit the grippers 19 to engage and release the socket.

To set the device up for operation, the ring or nut 5 is first passed on to the conduit and moved up the same, the shade being passed on to the conduit beneath the nut and the ring 17 of the bracket 16 beneath the 75 shade. The sleeve 3 may then be screwed on to the end of the conduit, and the socket 10 engaged between the bracket arms 18 as described, the ring 14 being screwed down against the gripper members. The shade is 80 then lowered until it rests on the flange 9 and the nut 5 is engaged with the thread 4 and screwed down until it engages the top surface of the shade, or engages and sufficiently compresses the eyelet 8, if such eyelet be used. The wires are of course connected to the socket before it is seated and while the shade is raised.

It will be apparent that if there is any necessity for repairing the socket or in any 90 way manipulating it, it is only necessary to unscrew the nut 5 and raise the shade when the socket is in full view and easily accessible, and it may be conveniently removed by loosening the sleeve 14 disengaging the 95 bracket arms 18. It may likewise be as conveniently replaced. It will also be apparent that this device may be applied to any conduit, the seating sleeve 3 being a portion of the fixture and adapted to be secured to any conduit by merely cutting a 100 thread thereon. Further there is no necessity for cutting or soldering the wires or for passing them in or out of the conduit when the socket is changed, repaired or inspected, 105 as the wires and socket in the device described are as easily accessible as are the sockets in the various fixtures used with glass reflector shades or without a reflector.

I have thus described specifically a single 110 embodiment of my invention in order that its nature and operation may be clearly understood. However, the specific terms herein are used in their descriptive rather than their limited sense and the scope of the 115 invention is defined in the claims.

I claim—

1. In combination a conduit having a threaded end, a sleeve internally threaded to engage the thread of the conduit and having a shoulder or flange at its lower end, a shade having an aperture to receive the portion of the sleeve above the flange so the shade rests on the shoulder, the sleeve being externally threaded above the abutment, a nut adapted to be passed over the upper end of the sleeve and threaded to engage the external thread thereon.

2. In combination a conduit having a threaded end, a sleeve internally threaded 130

- to engage the thread on the conduit and having an abutment or flange at its lower end, a shade having an aperture to admit the sleeve, so the shade rests on the abutment, 5 the sleeve being externally threaded above the abutment, a nut adapted to be passed over the upper end of the sleeve and engage the thread, a lamp socket and a multiple armed bracket, consisting of a ring encircling the sleeve above the flange and below the aperture in the shade, the ring having depending arms, the lower ends of the arms having gripping members for engaging the socket.
- 15 3. In combination a conduit having a threaded end, a sleeve internally threaded to engage the thread of the conduit and having an abutment or flange at its lower end, a shade having an aperture to receive the portion 20 of the sleeve above the abutment, the sleeve being externally threaded above the abutment, a nut adapted to be passed over the upper end of the sleeve and engage the thread, a lamp socket and a multiple armed bracket consisting of a ring encircling the sleeve above its flange and below the aperture in the shade and having depending arms, the lower ends of the arms having gripping members for engaging the socket,
- 25 30 the latter having a threaded member and an abutment between which the gripping members are clamped.
4. In combination a conduit, a sleeve to fit on the end of the conduit and means for removably securing the sleeve on the conduit, the sleeve having an abutment at its lower end, a shade having an aperture to fit and receive the upper end of the sleeve above the abutment so the shade rests on the abutment and means engaging the upper portion of the sleeve for clamping the shade against the abutment.
5. In combination a conduit, a sleeve having a support at its lower end and adapted 45 to fit on the end of the conduit and means for removably securing the sleeve, a shade having an aperture to receive the upper end of the sleeve so it rests on the support, the shade having in the aperture a soft metal eyelet or sleeve and means for forcing the shade down against its support compressing the eyelet whereby a tight joint is formed.
6. The combination of a pipe, conductor-wires extending through said pipe, a nipple fitting on the lower end of the pipe and adapted to be connected thereto from below, means for securing the nipple on the lower end of the pipe, an electric lamp connected to said conductor-wires, a shell around the lamp and having an aperture through which the nipple extends, and a collar around the nipple for securing the shell to the nipple, said collar when disconnected from the nipple permitting the shell to be raised on the pipe independently of the nipple.
7. The combination of a pipe, conductors extending through the pipe, a screw-thread at the lower end of the pipe, a nipple having a screw-thread engaging the thread on the pipe and having an abutment thereon, and having an exterior screw-thread, a nut having a thread for engaging the thread on the nipple, a shell removably held by the nut above the abutment, and a lamp beneath the pipe and connected to said conductors.
8. The combination of a pipe, conductors extending through the pipe, an exterior screw-thread at the lower end of the pipe, a nipple interiorly threaded to engage the thread on the lower end of the pipe and having a projecting abutment on its lower end and having an exterior thread above the abutment, a nut interiorly threaded to engage the exterior screw on the nipple and removable upward from the nipple, a shell held above the abutment on the nipple by said nut, the threaded opening in the latter being of sufficient size to permit the nut and shell to be freely raised on the pipe, and an electric-lamp beneath the receiver and connected to said conductors.

Signed at Philadelphia this sixth day of November 1912.
